CLAIM

[22] Filed: Nov. 12, 1985

The ornamental design for a octahedral residential
structure, as shown.

[52] U.S. Cl. D25/1; D25/32

[58] Field of Search D25/1, 4, 17, 22, 23,
D25/24, 25, 27, 30, 32

DESCRIPTION

FIG. 1 is a top plan view of the octahedral residential

structure showing my new design;

FIG. 2 is a side elevational view thereof, each additional
side elevational view thereof being substantially identi-
cal to that shown.
